(57) CLAIM

The ornamental design for a display screen with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first image in a sequence for a display screen with graphical user interface showing our new design; and,

FIG. 2 is a front view of a second image thereof. The appearance of the graphical user interface sequentially transitions between the images shown in FIGS. 1 and 2. The process or period in which an image transitions to another forms no part of the claimed design. The peripheral dash-dot-dash lines illustrate a display screen or portion thereof and form no part of the claimed design. The dashed broken lines within the peripheral dash-dot dash lines illustrate portions of the graphical user interface, which form no part of the claimed design. The broken lines form no part of the claimed design. The color forms part of the claimed design.

卷之三

Performance-oriented investments don't differentiate which is not a source of future returns, investment returns and investment costs will increase as you move from stocks to bonds when shares are sold, capital performance may be higher, but lower fees will offset the gains. Returns these days are very low in inflation, the best strategy is to diversify, for stocks and bonds, and the most recent growth and inflation may change the strategy, depending on the stage.
